US00D857696S

(12) **United States Design Patent** (10) Patent No.: **US D857,696 S**
Oh et al. (45) Date of Patent: **** Aug. 27, 2019**

(54) **TERMINAL FOR DATA PROCESSING DEVICE**

(71) Applicants: **CRUCIALTEC CO., LTD.**, Gyeonggi Do (KR); **CRUCIALTRAK, INC.**, Houston, TX (US)

(72) Inventors: **Dong Hyun Oh**, Seoul (KR); **Yong Hee Han**, Gwangju-si (KR)

(73) Assignees: **CRUCIALTEC CO., LTD.**, Gyeonggi-do (KR); **CRUCIALTRAK, INC.**, Houston, TX (US)

(**) Term: **15 Years**

(21) Appl. No.: **35/504,692**

(22) Filed: **Sep. 29, 2017**

(80) **Hague Agreement Data**

Int. Filing Date: **Sep. 29, 2017**

Int. Reg. No.: **DM/099773**

Int. Reg. Date: **Sep. 29, 2017**

Int. Reg. Pub. Date: **Mar. 30, 2018**

(30) **Foreign Application Priority Data**

Apr. 3, 2017 (KR) 30-2017-0015336

(51) **LOC (12) Cl.** **14-02**

(52) **U.S. Cl.**

USPC **D14/383; D14/384**

(58) **Field of Classification Search**

USPC D14/300, 383, 384, 356-358, 388, 408, D14/417, 496, 509, 203.6, 216, 228, 423, D14/229, 251; D16/200, 203, 204, 210

CPC G06Q 20/40145; G07C 9/00158; G07C 9/00563; G07C 9/00571; H04L 63/0861; G06F 21/32

See application file for complete search history.

(57) **CLAIM**

The ornamental design for a terminal for data processing device, as shown and described.

DESCRIPTION

1. Terminal for data processing device

1.1 : Back

1.2 : Bottom

1.3 : Front

1.4 : Left

1.5 : Right

1.6 : Top

1.7 : Perspective

(Continued)

The broken lines in the drawings show portions of the terminal for data processing device which form no part of the claimed design.

1 Claim, 7 Drawing Sheets
